WIGWAG SIGNAL

Lodovico Cristofoli, Kansas City, Mo.

Application June 2, 1941, Serial No. 396,310

6 Claims. (Cl. 172—126)

My invention relates to oscillating signals, and particularly to wig wag signals, the same being an improvement over the signal disclosed in my application for Letters Patent on Wig wag signal, Serial No. 237,271, filed October 27, 1938, patented July 29, 1941, Patent No. 2,251,116.

It is a purpose of my invention to provide a signal of the above mentioned character, that is extremely simple in construction and which can be very cheaply manufactured, and in which the signal arm will have a wide amplitude of movement. In order to accomplish this purpose the device is made up of a minimum number of parts, all of which can be manufactured in a simple manner and at low cost and can be cheaply assembled in position in the device.

It is a particular purpose of my invention to provide a device of the above mentioned character, which comprises a shaft-like member having the signal arm provided thereon, and means for oscillating said arm comprising an armature operatively connected with said arm and movable between a pair of electro-magnets, which are alternately energized, and to provide means for alternately energizing said electro-magnets comprising switching means including a contact element that is movable with the shaft carrying the signal arm, and a contact member comprising a pair of contact elements each connected with the windings of one of the electro-magnets, said contact elements being insulated from each other and being mounted obliquely to the path of movement of the contact member carried by the shaft, so that said contact members will have wiping engagement and so that contact will be made with the contact element on one side of said one contact member upon movement of the other contact member in one direction, and with the contact element on the other side of said one contact member when the movable contact member moves in the other direction.

It is another purpose of my invention to provide means for obtaining in a simple manner a wide amplitude of movement of the signal arm, by moving the shaft carrying the signal arm through a large arc, this being accomplished by means of a bail-like wire member mounted on the shaft and an armature made up of a pair of members that are spaced to provide a slot therebetween receiving the transverse portion of the bail-like wire member carried by the shaft loosely, and having diverging extensions between which said bail-like member is confined to prevent disengagement of the armature and the bail-like member, to thus provide a loose motion connec-

tion between the bail-like member and the armature, permitting said wide oscillation of the shaft upon movement of the armature back and forth under the alternate action of the electro-magnets.

It is another important purpose of my invention to provide means for returning the shaft and the moving parts carried thereby, as well as the armature, to a central position, comprising resilient means and means operatively connecting said resilient means with the oscillating shaft, comprising a pair of arms with which said resilient means is connected, that are alternately engageable by said bail-like member carried by the shaft, to resist movement of said shaft yieldingly in opposite directions.

Other objects and advantages of my invention will appear as the description of the drawing proceeds. I desire to have it understood, however, that I do not intend to limit myself to the particular details shown or described, except as defined in the claims.

In the drawing:

Fig. 1 is a vertical sectional view through my improved signal device, on a somewhat enlarged scale.

Fig. 2 is a section taken on the line 2—2 of Fig. 1, the moving parts being in a different position than that shown in Fig. 1.

Fig. 3 is a section taken on the line 3—3 of Fig. 1, the moving parts being in a different position than that shown in Fig. 1.

Fig. 4 is a view in elevation of one of the contact members and its mounting.

Fig. 5 is a fragmentary side elevational view of the lever elements and the resilient centering means for the moving parts, and parts associated therewith, and

Fig. 6 is a detail section taken substantially on the line 6—6 of Fig. 1.

Referring in detail to the drawing, my improved wig wag signal is shown as comprising a casing made up of a pair of cup-like members 10 and 11 that are telescopically related. Mounted within said cup-like member 10 is a base plate 12 that is provided with a pair of upstanding ears 13, upon which the cores 14 of the electro-magnets 15 and 16 are mounted. Said base plate 12 also is provided with a pivot pin 17 fixed therein and having mounted thereon numerous moving parts of the device, and also serving as a mounting for one of the contact elements, as will be described below. Said base plate 12 also has an upstanding ear 18 thereon, to which is welded an angular bracket 19. Said bracket 19 has an opening 20 therein for pivotally receiving one end

of a tubular shaft 21, which is also mounted in a bearing opening 9 in the base plate 12 and an opening in the outstruck portion 22 of the member 10, a felt washer 23 being provided for preventing entrance of moisture into the housing made up of the members 10 and 11 around the shaft. Said tubular shaft is bent at right angles to provide the upstanding annular arm 24, which is provided with a mounting for the lamp 25 having a base 26, a conductor 27 leading to the center contact of said lamp 25 and the annular sleeve-like member 26 forming the other contact of the lamp bulb being grounded on the metal of the flaring portion 28 of the signal arm.

The signal arm is thus mounted for oscillation with the shaft 21 and it will be noted that the conductor 27, which is provided with insulation in a well known manner, extends out through an opening 29 in said shaft-like member and is connected with a terminal 30 on a contact element 31, which extends through openings in said tubular shaft 21 and is insulated therefrom by means of an insulating sleeve 32.

Cooperating with the contact member 31 to alternately energize the electro-magnets 15 and 16 is a contact member that is mounted on the post, or pin, 17. The end of the post, or pin, 17 remote from the base member 12 is slotted, as will be evident from Fig. 4, and mounted in the slot in said pin, or post, 17 are the contact strips 35 and 36, insulating material 33 being provided between the walls of the slot in the member 17 and said strips 35 and 36, and an insulating element 34 being mounted between the contact strips 35 and 36. Said strips 34, 35 and 36 are, preferably, secured together by means of an insulating rivet 62. The thickness of the various elements is somewhat exaggerated in the drawing, said contact strip 35 being of thin sheet metal, and the contact strip 36 being of thin sheet metal, while the insulating strip 34 is, preferably, of thin fibrous sheet material, or other thin sheet insulation, as are the insulating members 33. The contact strip 35 is connected by means of a conductor 37 with the winding 15 of one of the electro-magnets, while the contact strip 36 is connected through the conductor 38 with the winding 16 of the other of the electro-magnets. It will be noted that said contact strip is twisted between the ends thereof, so as to have the transverse axis thereof extend obliquely to the direction of movement of the contact element 31 as the same oscillates back and forth with the shaft 21. While in the mounting shown, the contact member made up of the two contact elements 35 and 36 with the insulating element 34 therebetween, is shown as being twisted to obtain this relative position to said contact member 31, the important thing is that the direction of extent thereof is obliquely to the direction of movement of the movable contact member 31. Said movable contact member may be made of any desired material and of any suitable shape, and may be provided with a tapered end portion 39 as shown, it being only important that the contact member 31 be of such shape, size and extent that the same will properly engage the contact member comprising the contact strips 35 and 36 that a wiping engagement will be had with one contact strip 35 with the movement of the contact element 31 in one direction, and the other contact strip 36 when the movement of the contact member 31 is in the opposite direction. It will be obvious that when the contact element 31 is moving in the direction indicated by the ar-

row in Fig. 6 the same will have a firm wiping engagement with the contact strip 35 moving transversely across the face thereof, and when moving in the opposite direction will have a firm wiping engagement with the contact element 36 moving transversely of the face thereof. The contact element 31, preferably, engages the cooperating contact member having the contact elements 35 and 36 at the tapered end portion 39 thereof. It is obvious that the contact element having the strips 35 and 36 will yield as the contact member 31 moves thereacross, the strips 35 and 36 being made of material that is somewhat resilient.

The post-like member 17 serves as a pivot pin for the armature made up of a pair of strips of flat, soft iron 40, which are provided with arcuate portions 41 extending around the pivot pin 17, said arcuate portions being shown as being slightly spaced, as at 42, although such spacing is not necessary. The arcuate portions 41 form an eye or pivot member that embraces the pivot pin 17 to pivotally mount said armature thereon, and preferably, a washer 43 is mounted between the base member 12 and the armature. Each of said soft iron strips 40 is provided with a reduced portion forming a finger, said reduced portions being offset from the main body portions of the members 40 at 44, so as to space the substantially parallel portions 45 of said fingers from each other, to provide a slot 46 therebetween for a purpose to be described below. Said fingers 46 are inclined away from each other at 47 to provide diverging portions on said fingers extending from said socket and are curved at 48 and extended toward each other to provide the portions 49 that are welded or otherwise secured together to form a transversely elongated loop surrounding the hollow shaft 21. While the portion extending around the shaft is not absolutely necessary, it can be utilized to serve as means for limiting the movement of the armature. Said strips forming the armature are, preferably, secured together in any suitable manner face to face, as by means of a rivet 50.

Mounted on the hollow shaft 21 is a bail-like wire member having the transversely extending portion 51 and the legs 52 and 53, which are extended through aligning openings in the tubular shaft 21 and have the ends thereof bent over as at 54, to secure said bail-like member in position on said shaft. The thickness or width of the material of the transverse portion 51 of the bail-like member is less than the spacing of the parallel portions 45 of the reduced fingers on the armature forming the slot-like socket 46, whereby said bail-like member will have play, or fit loosely, for oscillation between the portions 45 of the armature. It will thus be seen that a loose motion connection is provided between the armature and the shaft through the bail-like member, and that the bail-like member will leave the slotted socket portion 46 formed in the armature, and travel along the inclined portions 41 of the fingers as the armature and the signal arm 24 reach the limit of their movement in either direction.

Means is provided for bringing the moving parts back to a central position with the armature and bail-like member located substantially in alignment with each other, comprising a pair of arms, or levers, 55 and 56, the arrangement of said means being shown more in detail in Fig. 5. Each of said members 55 and 56 has an opening

57 therein receiving the hollow tubular shaft 21 and a small opening 58 in the extremity thereof spaced from the shaft, each of said levers or arms tapering from the shaft receiving end thereof to the end thereof having said opening 58 therein. Resilient means is provided which is connected with each of the levers 55 and 56 and is also connected with a mounting spaced from said levers, so that as said levers are moved from a central position said resilient means will be put under tension to yieldingly resist such movement and to return said levers to a central position. In the form of the invention shown, said resilient means comprises a relatively long, but light, coil tension spring 59, which has the opposite ends thereof secured in the openings 58 and extends around a sleeve-like member 60 mounted on the pivot pin 17 rotatably, said sleeve-like member being, preferably, grooved on the face thereof, as will be obvious from Fig. 1, to retain the spring 59 in position on the pulley-like member 60. The transverse portion 51 of the bail is mounted between the two lever members, so that when the parts are in a central position said transverse portion 51 of said bail will lie between the two lever members 55 and 56 and be in engagement with both thereof.

When the device is set in operation, and presuming that the contact member 31 is in engagement with the contact strip 36, the armature comprising the strips 40 will be attracted by the electro-magnet having the winding 16, as the circuit will be completed from the conductor 61, which is connected with the terminal 30 on the member 31 through said member 31, and the contact strip 36 and conductor 38 to the winding 16, the other end of said winding being grounded to the casing of the apparatus, as is also the other end of the supply circuit to which the conductor 61 extends. The energization of the electro-magnet 16 will continue until the end 39 of the contact 31 has traversed the contact strip 36 transversely. After the contact element 31 leaves the contact strip 36 the momentum of the parts will carry the signal arm 24 to substantially the position shown in Fig. 3, the spring 59 being then tensioned as shown, due to the fact that the arm 55 will have been carried to the right in Fig. 1 by means of the bail-like member, due to engagement of said transverse portion 51 thereof with the edge of the arm or lever 55. The spring 59 will then act to return the parts toward a central position and the contact member 31 will then be moving in the direction of the arrow indicated in Fig. 6, whereupon said contact member will engage the contact strip 35, which extends obliquely to the path of movement of the member 31, flexing the contact member made up of the strips 35 and 36 and the insulating strip 34 and causing a wiping engagement across the face of the contact strip 35 by the member 31. Upon such engagement the winding 15 is energized and the armature is attracted thereby, continuing the movement of the member 31 toward the left in Fig. 6 until it has traversed the face of the contact strip 35 transversely, the circuit then being broken that was previously established to the winding 15 from conductor 61 through contact 31, contact strip 35, conductor 37 and winding 15 to the ground, but the momentum of the parts will carry the signal arm 24 to an extreme position having an angle to the vertical, substantially equal to that shown in Fig. 3 for the member 24, but oppositely thereto. Whereupon the spring 59 will be tensioned

on the opposite side thereof from that shown in Fig. 3 to urge the lever arm 56 to return to a central position as the same will have been moved from the position shown in Fig. 3 to a position 5 considerably to the left thereof, due to engagement of the transverse portion 51 of the bail therewith. The contact member 31 will be carried along with the moving parts back toward the cooperating contact member made up of the contact strips 35 and 36 and will engage during such movement with the obliquely extending face of the contact strip 36 to re-establish the circuit to the winding 16, whereupon the cycle of movements above described will be repeated.

15 Due to the fact that the points of attachment at 58 of the spring 59 to the levers 55 and 56 are further apart, when in the position shown in Fig. 5, with the transverse portion 51 of the bail mounted therebetween, than the diameter of the pulley 60 around which said spring extends, the lengths of said spring extending from said levers toward said pulley will converge toward said pulley. A much weaker spring can be used, with this arrangement, than if a spring longitudinally aligning with said lever were provided, to return the parts to a central position, due to the fact that the resilient means exerts a sidewise pull on said levers, instead of being on dead center when the parts are in a central position. A 20 smaller damping action on the oscillation of the signal arm 24 will thus be exerted by the spring, permitting a much greater amplitude of movement thereof.

It will, of course, be obvious that the magnetic circuit is from the core 14 through the bracket 13, the member 12, the post 17 to the armature 40, in the case of either of the electro-magnets that may be energized by the switching means described.

40 What I claim is:

1. In a signal of the character described, a shaft, a signal arm extending therefrom, and means for oscillating said arm, comprising a pair of electro-magnets, an armature mounted for movement between said electro-magnets, means operatively connecting said armature and shaft to oscillate said shaft by movement of said armature between said electro-magnets, and means for alternately energizing said electro-magnets, comprising a pair of contact members, one of said contact members comprising a pair of contact elements insulated from each other, each connected with the winding of one of said electro-magnets, and the other contact member being mounted to be oscillated by said shaft in a path perpendicular to the axis of said shaft, the contact faces of said pair of contact elements being parallel and said parallel contact faces extending obliquely to a plane perpendicular to said axis.

2. In a signal of the character described, a shaft, a signal arm extending therefrom, and means for oscillating said arm, comprising a pair of electro-magnets, an armature mounted for movement between said electro-magnets, means operatively connecting said armature and shaft to oscillate said shaft by movement of said armature between said electro-magnets, and means for alternately energizing said electro-magnets, comprising a pair of contact members, one of said contact members comprising a pair of contact strips on opposite sides of said contact member secured together but insulated from each other, each contact strip being connected with the winding of one of said electro-magnets, and

the other contact member being mounted to be oscillated by said shaft in a path lying in a plane perpendicular to the axis of said shaft, the contact faces of said pair of contact strips being parallel to each other and extending obliquely to said plane, one of said contact members being yieldable transversely of said plane upon engagement of said contact members with each other, to provide a wiping contact alternately between the contact member on said shaft and each of said contact strips.

3. In a signal of the character described, a shaft, a signal arm extending therefrom, and means for oscillating said arm, comprising a pair of electro-magnets, an armature mounted for movement between said electro-magnets, means operatively connecting said armature and shaft to oscillate said shaft by movement of said armature between said electro-magnets, and means for alternately energizing said electro-magnets, said shaft having means for returning said armature to a central position comprising a pair of arms loosely pivoted on said shaft, resilient means connected with each of said arms to resist movement thereof from a central position and a member on said shaft engaging between said arms to alternately move said arms against the tension of said resilient means upon oscillation of said shaft in opposite directions.

4. In a signal of the character described, a shaft, a signal arm extending therefrom, and means for oscillating said arm, comprising a pair of electro-magnets, an armature mounted for movement between said electro-magnets, means operatively connecting said armature and shaft to oscillate said shaft by movement of said armature between said electro-magnets, and means for alternately energizing said electro-magnets, comprising a pair of contact members, one of said contact members comprising a pair of contact strips, an insulating strip mounted therebetween, means for holding said strips in assembled position with said contact strips exposed on opposite faces of said contact member, a mounting for said contact member, means for insulating said contact strips from said mounting, means connecting each of said contact strips with the winding of one of said electro-magnets, the other contact member being mounted to oscillate with said shaft in a path lying in a plane perpendicular to the axis of said shaft, said contact strips being mounted with the contact faces thereof extending obliquely to said plane in parallelism with each other, and resilient means tending to urge said other contact into a position in which the same engages one of said contact strips, at least one contact member of said pair being yieldable transversely of said plane upon engagement of said contacts to provide a wiping engagement between said other contact

10 and said contact strips alternately as said shaft oscillates.

5. In a signal of the character described, a shaft, a signal arm extending therefrom, and means for oscillating said arm, comprising a pair of electro-magnets, an armature mounted for movement between said electro-magnets, means operatively connecting said armature and shaft to oscillate said shaft by movement of said armature between said electro-magnets, and means for alternately energizing said electro-magnets, said shaft having means for returning said armature to a central position comprising a pair of arms loosely pivoted on said shaft, a roller 15 mounted on a fixed axis spaced from said shaft, a coil spring having the ends thereof connected with said arms and extending over said roller, to resist movement of said arms from a central position and a member on said shaft engaging between said arms to alternately move said arms against the tension of said resilient means upon oscillation of said shaft in opposite directions

20 6. In a signal of the character described, a shaft and a signal arm extending substantially 25 perpendicularly to said shaft connected to move in unison, means for mounting said shaft for rotation about its axis, and means for oscillating said shaft and arm comprising an armature mounted on a pivot spaced from the axis of said shaft, a pair of electro-magnets mounted in spaced relation between said axis and said pivot, means movable with said shaft for alternately energizing said electro-magnets, said armature 30 extending between said electro-magnets and comprising a pair of arms having parallel portions secured together in fixed relation and spaced at a point remote from said pivot to provide a slot in said armature, a wire bail on said shaft extending toward said armature and having a transverse portion normally loosely received in said slot, said arms having portions engaged by said transverse portion of said bail as said bail continues to move with said signal arm after said armature has reached the limit of its 35 movement in either direction to prevent disengagement of said bail from said armature, said engaged portions being straight and diverging from said slot at an oblique angle to said parallel portions and to each other and extending toward said shaft to define a gradually widening confining means for the transverse portion of said bail extending from said slot toward said shaft, whereby said signal arm has a much wider amplitude of movement than said armature, and 40 resilient means connected with said shaft to return said bail and armature to a central position after each energization of each of said electro-magnets.

LODOVICO CRISTOFOLI.
